UNITED STATES PATENT OFFICE.

GEORGE C. BLICKENSDERFER, OF ERIE, PENNSYLVANIA, ASSIGNOR TO THE UNITED STATES STORE SERVICE COMPANY, OF ALBANY, NEW YORK.

CONVEYER APPARATUS.

SPECIFICATION forming part of Letters Patent No. 359,991, dated March 29, 1887.

Application filed December 16, 1884. Renewed March 8, 1886. Serial No. 194,510. (No model.)

To all whom it may concern:

Be it known that I, GEORGE C. BLICKENSDERFER, a citizen of the United States, residing at Erie, in the county of Erie and State of Pennsylvania, have invented certain new and useful Improvements in Conveyer Apparatus; and I do hereby declare the following to be a full, clear, and exact description of the invention, such as will enable others skilled in the art to which it appertains to make and use the same.

This invention relates to that class of conveyer apparatus in which the track is elevated and the article to be carried hangs from a running-gear on the track.

The invention consists in improvements on the construction of the track, the switches, the elevator, and the car.

The apparatus as illustrated is adapted for what is known as a "store-service system of carriers;" but the invention is not limited to such service.

In an application filed by me on November 3, 1884, I show many of the devices here shown; but in that case the receiving and dispatching switches and the elevator were adapted to a single circuit-track system, while in this case they are adapted to a system having two tracks graded in opposite directions, which necessitates important changes. On the other hand, many of the novel appliances here shown, especially those which have for their object the prevention of derailment of the cars, may be applied with advantage to many of the existing types of conveyer apparatus.

In the accompanying drawings, Figure 1 is a perspective view of a station on the conveyer-line with the elevator down, as when a car is being loaded. Fig. 2 is the same view with the elevator in position to receive a car from the receiving-switch. Fig. 3 is a side elevation of the shipping-switch, showing the elevator in the position it occupies when dispatching a car. Fig. 4 is the same view as Fig. 3, but does not show the elevator, the purpose of the figure being to show an alternative construction of the guard a^2 . Fig. 5 is a perspective view of the elevator detached from other parts. Fig. 6 is a perspective view

of the dispatching-switch arm A^2 . Fig. 7 is a view looking from the section-line xx in Fig. 1 in the direction of the arrow, and shows an end view of an approaching car. Fig. 8 is a like view to Fig. 7, showing the car after the main wheels have been thrown up off the main line and switch-wheels brought down upon the switch-track. Fig. 9 is a side view of the car from the right of Fig. 7.

Like letters of reference indicate like parts in all the figures.

A is the line of track which grades from the salesmen's station to the main or central station. A' is the dispatching-switch, by which cars are transferred from the elevator to the main line A. A² is the arm by which the switch-track A' is moved. A³ is a movable frame carrying the arm A². A⁴ is the arch which supports the point of the switch-track A'.

B is the main track, which grades from the central station to the salesmen's stations. B' is a receiving-switch at a salesman's station. B² is a section of track on the elevator. B³ is an arm which supports the inner end of the switch B'. B⁴ B⁵ are the arches which support the point of the switch B'.

C is the elevator way or track. C' is a bracket attached to the way C, which supports the sheave c', over which the elevator-cord passes, and it also serves as a support for the sliding frame or bracket A³. D is the elevator frame or slide. D' is a rock-shaft pivoted in the frame D and supporting the track-section B².

E is the bracket or receiver of the car. E' E² E³ E⁴ E⁵ E⁶ mark the various parts of the frame-work of the car.

F F are the main wheels of the car. F' F' are the switch-wheels, and F² F² are guide-rollers.

The letters designating other parts will be referred to in place herein.

The construction, objects, and operation of parts will be best understood if the description thereof begins with a car as just entering a salesman's station, and follows it until it is dispatched from that station, and to this end I will first describe the car. (See Figs. 7, 8, and 9.)

The truck or trolley of the car is substan-

tially the same as shown in my previous application above referred to. The main wheels F F are on a cross-head, E⁶, which slides vertically on a standard, E⁵, and a trigger device, 5 e' e², holds the sliding part down until it is sprung by coming in contact with a finger, e³, at the station. When thus sprung, the main wheels are thrown up and the switch-wheels F' F' are brought to tread on the switch- 10 track B'.

The novel features provided on the trolley are the hooks e⁶, the shoulder e⁵, and the hook e⁴. The object of the hooks e⁶ is as follows: At the central station, when a car is to be sent 15 out on the line B, it is often desirable to set it on the track before it is ready to be sent out, and as the track grades the car has to be retained in some manner, and the most convenient way is to suspend the car on the track by 20 the hooks e⁶ until it is ready to start, and then lift it up and set it on its wheels. This is simply a convenience to the attendant.

The objects of the shoulder e⁵ and also of the hook e⁴ will appear farther on. Heretofore the receptacles or brackets of the cars have been made with full bails at each end, and when an article of greater length than the space between the bails was to be carried it had to be put in from the end. I have found 30 it to greatly add to the convenience of the car to support the basket by strong half-bails E', and thus leave one side and both ends of the basket free from obstructions. This construction can be quickly understood by observing 35 Fig. 7.

By reference to Figs. 1 and 2, it will be seen that the point of the switch B' is supported by two arches, B⁴ B⁴, and that the guides b⁴ b⁴ are also supported by both these arches. This 40 makes a very strong construction and holds all the parts firmly. It will also be seen that by these two arches I also support two guards, b³ and b⁵, by which b³ is arranged immediately below the main line B, and b⁵ is at one 45 side and above the switch-track B', and extends from the point to the inner end of the same. The relative position of this guard with relation to the track B' will be best observed in Figs. 7 and 8. The object of these 50 guards is to effectually prevent a car being derailed as it takes to the switch. Their operation is as follows: In Fig. 7 the car is still running on the main line B, and in Fig. 8 it is shown as on the switch-track. This change 55 took place while the car was passing under the arch B⁴ at the left of Fig. 1 by the trigger e' having been sprung by coming in contact with the finger e³.

It will be seen that if the change had not 60 taken place the end of the hook e⁴ would escape the guard b⁵, which is the case on all cars which pass the switch; and by observing Fig. 8 it will be seen that when the change took place the hook e⁴ embraced the guard b⁵. It 65 will also be seen that the shoulder e⁵ was brought up close under the guard b⁵. The

shoulder e⁵, I pad with leather or other material, and the guard b⁵, coming in contact with it, serves as a brake to check the momentum of the car, so that it will not pass onto the 70 switch too rapidly. The guides b⁴ prevent any vibratory movement of the car while passing or entering a switch, and the impingement of the shoulder e⁵ against the guard b⁵ prevents any upward rebound of the car as its switch-wheels are brought into tread on the switch-track, and as the car runs off on the switch the guard b⁵ and hook e⁴ prevent the car from swaying or vibrating as it runs on the curve 80 of the switch-track, and they also prevent derailment of the car. When the car reaches the end of the switch and runs off onto the track B² on the elevator, it is running perfectly steady, and its speed has been checked, so that it moves slow. 85

In the previous application referred to above, I showed the jointed track-bar B², the pivoted stop B⁵, the supporting-arm B³, the sliding frame D, the catch-lever D⁶, and catch-lug d⁶, all substantially as they are here shown; 90 but I did not show the bar B² attached to a rock-arm, D', so that it can be tilted, nor any of the automatic devices for holding or releasing the rock-shaft. In the aforesaid application the car, when dispatched from the elevator-bar B², was sent off at the opposite end of the bar from which it was received, while here it is sent back off the bar from the same end at which it was received. In this case the operation of receiving a car onto the bar B² 95 and lowering it down to the counter and drawing it up to the dispatching-switch is substantially the same as in the case referred to, and hence needs no description here. Fig. 5 clearly shows the construction of the elevator. 100 On the shaft D' there is a spring, d, which acts to hold the bar B² horizontally. At the opposite end of the shaft from the bar is a lever, D², which is engaged by a catch-button, D³. When these parts are engaged the shaft D' cannot be 110 rocked. A stop-catch, D⁴, limits the degree to which the shaft can be rocked when the catch D³ is disengaged from the lever D². The parts are kept in the position shown in Fig. 5, except when the elevator is brought into the 115 position shown in Fig. 3. A car while setting on the bar B² of the elevator rests on its switch-wheels, and it is prevented from being vibrated sideways by the finger E' on the car-frame resting under the stop D⁶ on the shaft D'. The 120 switch-switch A' keeps the position shown in Figs. 1 and 2, except when the elevator is brought up into the position shown in Fig. 3, and then it is moved on its pivot a' at its point. When the switch A' is in the position shown in 125 Figs. 1 and 2, cars can pass it freely on the track A. When it is in the position shown in Fig. 3, if a car should be passing on the line A, it will be stopped by the switch-track A' until it is lowered again into the position shown in Figs. 130 1 and 2. It is therefore advisable for the attendant to take notice of any approaching cars

on the line A before attempting to dispatch a car from the elevator, and avoid stopping the approaching car.

Connection between the bar B² and the switch-track A' and the elevation and inclination of the latter, and the dispatching of a car from the elevator onto the switch and thence onto the track, is effected as follows: As the elevator is drawn up, the rod c, which depends from the bracket C', comes in contact with the catch-button D³ and releases it from its hold on the lever D². About the same time the outer end of the bar B² was guided by the lug a on the arm A² and the hook a' on the bar B² into connection with the switch-track A'. As the movement upward of the elevator proceeds the frame D strikes against the sliding frame A³, which supports the end of the arm A², and lifts it up. As this movement takes place the track A' and the bar B² are both tipped, so as to form an inclined way, and the car runs down this inclined way, and its upper or main wheels are guided by the guide-arms a⁴ on the arch A⁴, so that they are set upon the track A, and the car proceeds on its course to the central station. If when a car is thus passing out of the switch A' onto the main track A a car from farther up the track should collide with it at that juncture, the one from above would be apt to be derailed. To prevent this I place under the main line the guard-rail a⁵, which, if the car should be lifted, will hit upon the shoulder e⁵ on the car, and would thus be prevented from being displaced, as the guard is so placed that the car cannot be lifted up far enough to allow its wheel-flanges to pass off of the track. In Fig. 4 the guard is shown as made of a flat bar set on edge, while in the other figures in which it appears it is made of a wire.

As soon as a car has been dispatched, as above described, the attendant lowers the elevator. This allows the frame A³, with the arm A², to drop back into the position shown in Figs. 1 and 2, and as soon as this occurs the spring d rocks the shaft D' so as to bring the track B² horizontal, and the catch-button D³ is released from the rod c and engages with the lever D², bringing all the parts into the position shown in Figs. 1, 2, and 5.

What I claim as new is—

1. In a conveyer service apparatus, the combination, substantially as herein set forth, of two main tracks, one of which conveys cars from the central station to the way-stations and the other from the way-stations to the central station, two switch-tracks at each way-station, one for receiving cars and the other for dispatching cars, the latter of which switches is pivoted at its point and vertically movable at its inner end, a vertical elevator-way in connection with both said switches, and, finally, an elevator-frame moving on said way and bearing a track-section, onto which cars pass from the receiving-switch and from which they pass onto the dispatching-switch.

2. In a conveyer apparatus, the combination, substantially as herein set forth, of two main tracks, one of which leads from the central station to the way-stations and the other from the way-stations to the central station, two switch-tracks at each way-station, one for receiving cars and the other for dispatching cars, the latter of which is pivoted at its point and vertically movable at its inner end, a vertical elevator-way in connection with both said switches, and, finally, an elevator-frame moving on said way and bearing a track-section, which is pivoted to said frame so as to tilt and engage with and lift the vertically movable end of the said dispatching-switch.

3. In a conveyer apparatus, the combination, substantially as herein set forth, of two main tracks, one leading from the central station to the way-stations and the other from the way-stations to the central station, a switch-track connecting with the latter main track at each way-station, which is pivoted at its point and vertically movable at its inner end, so that its grade may be changed, an elevator-way, and an elevator-frame sliding on said elevator-way, and bearing a track-section which engages with the said pivoted switch-track and elevates its inner end and forms therewith a continuous track for the passage of cars from the elevator to the main line.

4. In a conveyer apparatus, the combination, substantially as herein set forth, of a vertical elevator-way, a tilting dispatching switch-track, and a tilting elevator-track, which engage with each other at the time of tilting and form a continuous inclined track, for the purposes mentioned.

5. In a conveyer apparatus, the combination, substantially as herein set forth, of the main track A, the tilting switch-track A', a vertical elevator-way, an elevator-carriage moving on said way and having mounted thereon the tilting elevator-track B², and intermediate connections, said track B² being adapted, substantially as shown, to engage with said switch-track A', and tilt the same and itself simultaneously as the elevator moves up.

6. In a conveyer apparatus, the combination, substantially as herein set forth, of the main track A, the tilting switch-track A', a vertical elevator-way, an elevator-carriage moving on said way and having mounted thereon the tilting elevator-track B², the rock-shaft D', arm D², catch-button D³, and means, substantially as shown, for releasing said catch when in the upward movement of the elevator the tracks A' and B² engage.

7. In a conveyer apparatus, the combination, substantially as herein set forth, of the main track A, the tilting switch-track A', a vertical elevator-way, an elevator-carriage moving on said way and having mounted thereon the tilting elevator-track B², the rock-shaft D', arm D², catch-button D³, and the depending rod c.

8. In a conveyer apparatus, the combination, substantially as herein set forth, of the main track A, the tilting switch-track A', the arm A², the sliding bracket A³, the elevator-way C, the elevator D, the rock-shaft D', and the elevator-track B³.

9. In a conveyer apparatus, the combination, substantially as herein set forth, of the main track A, the tilting switch-track A', the arm A², the sliding bracket A³, the elevator-way C, the fixed bracket C', the rod e, the elevator D, the rock-shaft D', the track-section B², the arm D², and the catch-button D³.

10. In a conveyer apparatus, the combination, substantially as shown, of the switches A' and B', the elevator-way C, the elevator D, the bracket C', supporting the sheave e', and the elevator-cord, as shown.

11. In a conveyer apparatus, the combination, substantially as herein set forth, of the switches A' and B', the elevator-way C, the elevator D, the rock-shaft D', the track B², stop D⁶, and car with finger E.

12. In a conveyer apparatus, the combination, substantially as herein set forth, of the track B, switch B', guard b³, and a car having

stop or shoulder e⁶, which registers with said guard.

13. In a conveyer apparatus, the combination, substantially as herein set forth, of the track B, switch-track B', guard b⁵, and a car having a hook for engaging said guard.

14. In a conveyer apparatus, the combination, substantially as herein set forth, of the track B, the switch-track B', the arches B⁴ B⁴, the guards b³ and b⁵, and a car having the stop e⁶ and hook e⁴.

15. In a conveyer apparatus, the combination, substantially as herein set forth, of the track B, the switch B', the guards b³ and b⁵, the guides b⁴ b⁴, and the arches B⁴ B⁴.

16. In a conveyer apparatus, the combination, substantially as herein set forth, of the track B, switch B', guard b⁵, guides b⁴ b⁴, and the arches B⁴ B⁴.

In testimony whereof I affix my signature in presence of two witnesses.

GEO. C. BLICKENSDERFER.
